US00D937689S

(12) **United States Design Patent** (10) Patent No.: **US D937,689 S**
(45) Date of Patent: **** Dec. 7, 2021**

(54) **THERMOSTAT**
(71) Applicant: **BELIMO Holding AG**, Hinwil (CH)
(72) Inventors: **Daniel Aeberli**, Balterswil (CH);
Walter Jungen, Adliswil (CH)
(73) Assignee: **BELIMO HOLDINNG AG**, Hinwil
(CH)

(**) Term: **15 Years**

(21) Appl. No.: **35/508,771**

(22) Filed: **Sep. 5, 2019**

(80) **Hague Agreement Data**

Int. Filing Date: **Sep. 5, 2019**
Int. Reg. No.: **DM/205146**
Int. Reg. Date: **Sep. 5, 2019**
Int. Reg. Pub. Date: **Mar. 6, 2020**

(30) **Foreign Application Priority Data**

Mar. 8, 2019 (CH) 144604
(51) LOC (13) Cl. 10-04

(57) **CLAIM**

The ornamental design for a thermostat, as shown and
described.

DESCRIPTION

- 1.1 : Right
1.2 : Perspective
1.3 : Back
1.4 : Bottom
1.5 : Left
1.6 : Front
1.7 : Perspective
1.8 : Top

Portions of the article shown in broken lines form no part of
the claimed design.

1 Claim, 8 Drawing Sheets
